UNITED STATES PATENT OFFICE

163,893

WATCH BAND

Samuel Moanfeldt, New York, N. Y., assignor to
Chambers Mfg. Co., New York, N. Y., a firm

Application June 28, 1950, Serial No. 10,815

Term of patent 14 years

(Cl. D45—4)

To all whom it may concern:

Be it known that I, Samuel Moanfeldt, a citizen of the United States of America and a resident of the city of New York, in the county of Kings and State of New York, have invented a new, original, and ornamental Design for a Watch Band, of which the following is a specification, reference being had to the accompanying drawing, forming a part thereof.

Fig. 1 is a plan view of a watch band, showing my new design.

Fig. 2 is a side elevational view of the watch band, portions of the chain elements being broken away for convenience of illustration as indicated by the broken lines.

Fig. 3 is a bottom view thereof.

The dominant feature of my design for a watch band resides in the flexible chain portions thereof, said chain portions being comprised of both domed and flat links and being characterized by the arrangement of these links.

I claim:

The ornamental design for a watch band, substantially as shown and described.

SAMUEL MOANFELDT.
